TABLE TOP, COUNTER TOP, OR THE LIKE

Walter G. Dieter, William G. Ritton, and Paul M. Hull, Parkersburg, W. Va., assignors to Libbey-Owens-Ford Glass Company, Toledo, Ohio, a corporation of Ohio

Application October 18, 1938, Serial No. 235,632

2 Claims. (Cl. 311—106)

The present invention relates to an improved compound slab or panel for use as table tops, counter tops, and the like.

The compound slab or panel herein provided consists broadly of a facing sheet or plate of opaque structural glass or other frangible material provided with a reinforcing backing permanently secured thereto by an interposed sheet or layer of strengthening material and also having a preferably metallic band or rim arranged at one or more edges of the facing sheet and backing for protecting the said facing from being chipped or fractured.

An object of this invention is to provide a compound slab or panel of the above character having an improved type of reinforcing backing coupled with novel means for permanently securing the said backing to the facing sheet, thereby resulting in a more serviceable, durable construction.

Another object of the invention is to provide a compound slab or panel of the above character having novel means for effectively protecting the edges of the facing sheet against injury through blows against the same; said protective means having a portion thereof embedded in said backing so that it is firmly and permanently secured in place.

Another object of the invention is to provide a compound slab or panel of the above character embodying novel means for facilitating the aligning of the slabs or panels, especially when used as a counter top or the like, to provide a sounder, more rigid construction and minimize, if not entirely prevent, chipping or spalling of the edges of adjacent facing sheets.

Other objects and advantages of the invention will become more apparent during the course of the following description, when taken in connection with the accompanying drawings.

In the drawings, wherein like numerals are employed to designate like parts throughout the same:

Fig. 1 is an edge view of a table top formed of a compound slab or panel embodying the present invention;

Fig. 2 is a perspective sectional view of a portion thereof;

Fig. 3 is a plan view of a counter top formed of compound slabs or panels also embodying the invention;

Fig. 4 is a sectional view taken substantially on line 4—4 of Fig. 3; and

Fig. 5 is a perspective view of one of the compound slabs or panels having dowel members

associated therewith for connecting adjacent slabs or panels together and for also facilitating the aligning thereof when installed.

By way of example only, the invention has been illustrated in Figs. 1 and 2, as being applied specifically to a table top, while in Figs. 3, 4 and 5 it has been illustrated in connection with the making of a counter top or the like. However, it is to be understood that the invention is not restricted to the particular uses herein disclosed but is applicable wherever such a compound slab or panel may be advantageously employed.

With reference first to Figs. 1 and 2 of the drawings, the compound slab or panel comprises a facing sheet or plate 5 which, while preferably of opaque structural glass, may be of any other vitreous material. Underlying the facing sheet 5 is a reinforcing backing or body portion 6 arranged over the entire area of said facing and permanently secured thereto by an interposed non-brittle sheet or layer of strengthening material 7. The backing 6 is adapted to be formed from a suitable cementitious material, preferably gypsum, while the strengthening material 7 preferably consists of a sheet of roofing material having a fibrous base coated with a bituminous substance such as asphaltum.

One type of strengthening material which has been used with satisfactory results is that made and sold by the Ruberoid Company, of Erie, Pa., under the trade name "Ru-ber-oid." This type of material is relatively inexpensive, will stand up over a relatively long period of time, and does not deteriorate. By forming the backing 6 of gypsum and uniting the same to the facing sheet 5 with the non-brittle sheet of roofing material 7, there is provided a compound slab or panel of exceptional strength and durability.

The sheet of strengthening material 7 and backing 6 serve to greatly reinforce the facing sheet 5 and, when structural glass is used, permit the use of a relatively thinner sheet than heretofore, thereby reducing the cost of the unit. Another advantage is that even though a crack might develop in the glass facing it would hardly be perceptible on such a unit, as the sheet of strengthening material would prevent the crack from opening. Also, if the glass facing sheet should become broken, the strengthening material would retain the pieces in much the same manner as safety glass. The sheet of strengthening material serves further to cushion the facing against shock and blows, thereby greatly increasing its strength and resistance to breakage.

In order to protect the edges of the facing sheet

5 from blows and the like which might result in the chipping or fracturing thereof, as well as for covering the edges of the backing 6 to give a neater and more finished appearance, there is arranged around the perimeter of the compound slab or panel a protective rim or band 8. As shown, this rim covers not only the edges of the facing sheet but also extends down far enough to effectually conceal the edges of the backing. The protective rim 8 may be of any desired cross section and likewise of any desired material; although it is preferably of metal. The metal rim can, if desired, be coated upon its outer surface with a colored enamel to provide an attractive trim for the table top or it can be suitably striped with enamel to match the glass facing whereby to create a massive effect and the illusion of a heavy slab or panel.

For the purpose of securing the metal rim 8 to the compound slab or panel without marring the facing sheet 5, it is provided with suitable anchoring means adapted to be embedded in the cementitious backing 6. As here shown, the anchoring means comprises a flange or tongue 9, carried by and extending inwardly at substantially right angles to the rim 8 and provided at its free end with an enlarged key or anchoring portion 10 in the form of a hollow bead. The flange 9 and anchoring portion 10 may extend the entire length of the metal rim or a plurality of spaced locking elements can be provided, as desired.

When forming the compound slab, the sheet of strengthening material 7 is first adapted to be secured to the bottom surface of the facing sheet 5. This can be accomplished by treating one side of the sheet 7 with turpentine and permitting it to stand until it becomes tacky. The sheet is then placed upon the bottom surface of the facing, with the tacky side in contact therewith and the said sheet weighted down and allowed to stand the required length of time until it becomes firmly secured to the facing.

There is then provided a suitable mold of the desired shape and size and the facing sheet is laid upon the bottom of the mold with the sheet of strengthening material facing upwardly. The metal rim 8 is also properly associated with the facing in the mold. The upper side of the sheet of strengthening material is then treated in the same manner with turpentine until it also becomes tacky, whereupon the cementitious material forming the backing 6 is poured into the mold upon the sheet of strengthening material 7. The cementitious material is then allowed to set whereupon the compound slab is ready for use. When the material forming the backing 6 hardens, it will be readily seen that the enlarged anchoring portions 10 of the metal rim will be securely embedded therein, thus effectively preventing the metal rim from becoming loose or disengaged from the compound slab.

Although it is preferred to make use of gypsum for the backing 6 and a sheet of roofing material for the strengthening layer 7 as set forth above, it is to be understood that the invention is not limited to the use of these particular materials. On the other hand, a layer of mastic or plastic cement may be substituted for the sheet of roofing material 7 and likewise the backing 6 may be formed of cement-plaster, concrete, or a similar material. Also, the backing might be lightened by mixing asbestos, cork, sawdust, rock wool, or the like with the cementitious material.

When gypsum is used, it is preferred that the

lower portion of the metal rim 8, which comes in contact with the gypsum, be provided with a coating of mastic or cement 11 to form a suitable bond between the gypsum and metal rim as well as to retard rusting of the rim. The flanges 9 and anchoring portions 10 may be similarly coated to retard rusting. The cementitious backing 6 is also preferably, although not necessarily, reinforced with a layer of wire mesh or metal lath 12. When using the slab or panel as a table top, it is adapted to be secured to a suitable supporting standard 13 or the like in any desired manner.

In Figs. 3 and 4 of the drawings is shown specifically a portion of a counter top or the like, including the two compound slabs or panels 14 and 15 provided by the present invention. These slabs are arranged side by side in abutting relation and each comprises a facing sheet 16 of opaque structural glass or other frangible material, a reinforcing backing 17 of suitable cementitious material, and an interposed sheet or layer of strengthening material 18 for permanently securing the facing and backing to one another. The outer exposed edges of each slab are provided with a metal band or rim 19 which is disposed opposite the edges of the facing sheet and likewise covers the edges of the backing. The rim is secured in place by suitable anchoring means including the enlarged hollow bead 20 embedded in the backing 17. The lower portion of the metal rim which comes in contact with the cementitious material can be coated with a layer of mastic or cement 21 to form a suitable bond between the rim and cementitious material and also retard rusting of the rim. The reinforcing backing 17 may consist of gypsum, cement-plaster, concrete, or other desired cementitious material, while the strengthening material 18 may consist of a sheet of "Ru-ber-oid" or other roofing material or a layer of mastic or plastic cement.

When laying the compound slabs or panels 14 and 15 side by side, the abutting edges of adjoining slabs are adapted to be interlocked with one another in a manner not only to secure them in proper position but to facilitate the aligning thereof. To this end, the backing of one of the slabs, and as here shown slab 14, is provided at one edge with a transverse groove 22, while the backing of slab 15 is provided with a projecting tongue 23 adapted to fit snugly in groove 22. This tongue and groove arrangement greatly facilitates the aligning of the slabs during installation to provide a sounder and more rigid construction while preventing chipping or spalling of the adjacent edges of the facing sheets such as would be apt to occur were they not held in perfect alignment. Dishes and glassware can also be slid over the facing sheets, aligned in this manner, without danger of breakage.

According to the invention, the backing of each slab also projects slightly beyond the adjacent edge of the facing sheet at the end provided with the tongue or groove so as to further minimize danger of chipping or spalling of the edges of the facings when abutting the slabs. As shown, the abutting edges 24 and 25 of slabs 14 and 15 respectively project slightly beyond the corresponding edges of the facing sheets so that when the slabs are moved into interlocking relation and the edges 24 and 25 abut one another there will be a slight space or gap between the corresponding edges of the facing sheets. The joint

thus created can be filled either with a pointing compound 26 or it can be cushioned with a strip of cork tape or the like and then pointed. This slight separation of the adjoining edges of the facing sheets coupled with the strengthening material beneath the said sheets will effectively take care of any variation in the contraction and expansion of the facings and backings.

If desired, instead of using the tongue and groove construction illustrated in Figs. 3 and 4 for lining up adjacent slabs, the arrangement illustrated in Fig. 5 may be employed. The slab here disclosed also consists of a facing sheet 27 of opaque structural glass or other frangible material, a backing 28 formed from a suitable cementitious material and an interposed layer or sheet of strengthening material 29 for securing the facing and backing together. Arranged along opposite sides of the slab are the metal rims or bands 30-30 provided with the inwardly directed flanges 31-31 terminating in the hollow beads 32-32. When used to form a counter top or the like, the adjacent slabs are adapted to be connected together by the fiat metal dowel members 33-33 which are inserted within the hollow beads 32-32 of adjoining slabs. These dowel members or pins are adapted to be of such shape as to snugly fit within the beads 32 so as to prevent relative movement therebetween. They will thus serve to effectively line up the outside edges of the metal rims of adjacent slabs as well as the upper surfaces of the facing sheets.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

We claim:

1. In a table top, counter top or the like, a plurality of compound slabs or panels arranged side by side in abutting relation, each comprising a frangible facing sheet, a reinforcing backing beneath and secured to said facing sheet, and a protective metal rim extending along the exposed edges of each slab and having a portion thereof embedded in the reinforcing backing, the reinforcing backings of adjoining panels being provided at their meeting edges and inwardly of the opposite side edges thereof with interlocking tongue and groove portions whereby said slabs may be aligned with one another, the opposite ends of said groove being closed and engageable by the ends of said tongue to prevent transverse relative movement between the said slabs.
2. In a table top, counter top or the like, a plurality of compound slabs or panels arranged side by side in abutting relation, each comprising a frangible facing sheet, a reinforcing backing beneath and secured to said facing sheet, and a protective metal rim extending along the exposed edges of each slab and having a portion thereof embedded in the reinforcing backing, the meeting edges of the reinforcing backings of adjoining slabs projecting beyond the corresponding edges of the facing sheets and being provided with interlocking tongue and groove portions spaced inwardly from the side edges thereof to facilitate the alignment of the slabs, the opposite ends of said groove being closed and engageable by the ends of said tongue to prevent relative transverse movement between the said slabs, the projecting meeting edges of adjacent slabs serving to space the corresponding facing sheets from one another.
